UNITED STATES PATENT OFFICE

2,641,167

BAG BOTTOM FORMING DEVICE

Franco Gramegna, Milan, Italy, assignor to St. Regis Paper Company, New York, N. Y., a corporation of New York

Application October 9, 1950, Serial No. 189,271

11 Claims. (Cl. 93—22)

1

This invention relates to bag bottom forming apparatus, and more particularly to apparatus for automatically opening the extremities of bag tubes and thereafter forming side and corner flaps thereon preparatory to final forming of the bag bottom.

This invention includes improvements of certain of the elements of the bag bottom forming apparatus disclosed in the copending United States patent application Serial No. 48,820, filed September 11, 1948, for Bag Bottomer, by Edwin E. Burroughs (now Patent No. 2,570,047). Such new elements can be employed in a device now in use in the United States of America.

Apparatus of this character suggested in the past, for automatically opening the extremities of bag tubes and thereafter forming the side and corner flaps, have been quite successful with bag tubes formed of many types of paper, such bag tubes including the multi-ply and single ply varieties. However, such prior apparatus have not been entirely successful with bag tubes composed of certain other types of paper. Multi-ply bag tubes formed of ordinary kraft paper of the variety normally manufactured in the United States for bag use are relatively stiff due to the relative stiffness of such paper. That is, apparatus of this character suggested in the past has proven quite satisfactory for the stiffer types of kraft papers but has not fulfilled all desired results with respect to the less stiff varieties.

One of the objects of the present invention is to overcome the above difficulties or to reduce same to insignificance.

The invention, in one aspect thereof, comprises mechanism for use with an automatic bag bottom forming apparatus, the latter having a bag tube conveyor including spaced gripping means for consecutively gripping a plurality of bag tubes near opposite extremities thereof and moving same in succession relative to the apparatus in preselected spaced relationship along a common path, the improved elements including improved tube end opening means and tube end spreading means.

The novel tube end opening means comprises a pair of endless belts, each being mounted upon a pair of wheel members and each having a like plurality of suction cups mounted in spaced relation thereon, such cups coacting to open the end of the bag tubes. The endless belts can be in the form of, for example, sprocket chains and are positioned side-by-side in substantially the same plane whereby a "side run" of one belt is adjacent a side run of the other belt. The end-

2

less belts and the cups thereon are movable in synchronism whereby opposed pairs of cups are movable in phase with one another, each such pair including one cup on each belt. The opening of a tube end is effected by first permitting the suction cups to gain a grasp upon opposite sides of a tube end through the intermediary of vacuum created therein and thereafter separating the cups. Each pair of suction cups, of course, moves with its respective bag tube during a substantial portion of its travel along the above-mentioned common path and during such portion of the travel of the cups are able to gain an adequate grip upon the tube ends. The separation of a pair of the suction cups is effected preferably by cam means, the suction cups being pivotally mounted upon their respective belts in such a manner that their relative angular relationship is under the influence of such cam 10 while the pair of cups is moved linearly in the direction of the tube ends or in the direction of the bag tube conveyor. By means of such cam, the angular relation of a pair of suction cups can be changed from a closed position progressively to an open one whereby a tube end grasped thereby is thus opened to a desired extent and simultaneously said cups and tube end are undergoing linear or translational movement in the direction of the motion of the bag tube conveyor.

The novel tube end spreading means (as opposed to the tube end opener) is also referred to as a bag bottom flap-forming device and comprises a plurality of spreader units which are movable in a novel manner upon a conveyor 15 which maintains each spreader unit in a constant attitude relative to the path of movement of the bag tube, that is, a longitudinal axis of each unit is maintained in a common attitude relative to the path of movement of the bag tubes, for example, vertical to the plane over which the bag tubes move. The means for so controlling the movement of the several spreader units causes each unit to be lowered into an open tube end shortly after the opening action of said suction 20 cups, whereby such lowering of the unit has a pressing or ironing action upon the tube end so opened. After such lowering of a spreader unit the latter is moved along with the moving tube end in linear or translational movement and novel flap-forming or flap-folding mechanism is actuated to form the leading and trailing corner flaps and coincidentally the side flaps of the bag bottom. For this purpose each spreader unit is provided with a pair of spreader tongues which 25 can be retracted or extended relative to the

spreader unit, such tongues being guided whereby the outer or flap-forming extremities thereof are extended to opposite directions synchronously. Such tongues constitute flexible plates or metallic strips which are flexible in one direction and which can be drawn up into a frame of the spreader unit whereby they are substantially vertical relative to the plane of movement of the bag tubes and the plane of movement of the spreader unit, such vertical and parallel portions of the spreader tongues constituting substantially the entire lengths thereof. Thus each spreader unit includes a pair of flexible tongue members retractilely mounted in guides formed therein with the outer ends thereof directed in opposite directions. Each outer end of a tongue is provided with a V-shaped corner flap-shaping member secured thereto. Suitable means are provided for synchronously extending and retracting the pairs of tongue members in pre-selected relationship with the movement of the bag tube conveyor whereby a spreader unit, as above mentioned, may be lowered into each on-coming opened tube end and can be moved along therewith at the same speed thereof and the corner and side flaps positively formed therein by said tongue members. Thereafter adhesive is applied to the flaps and the bag bottom is formed by folding the flaps as will appear below.

Various, further and more specific objects, features and advantages of the invention will clearly appear from the detailed description given below taken in connection with the accompanying drawings which form a part of this specification and illustrate, by way of example, preferred arrangements of apparatus for carrying out the invention. The invention consists in such novel combinations of features and method steps as may be shown and described in connection with the apparatus herein disclosed.

In the drawings:

Figs. 1 and 1a are respectively the first and second halves of an automatic bag bottom forming apparatus which is analogous to that disclosed in copending application Serial No. 48,820, filed September 11, 1948, by Edwin E. Burroughs (now Patent No. 2,570,047) with the exception that the tube end opener and tube end spreader means embody improvements which acting alone and in combination with the other elements comprise the present invention;

Fig. 2a to Fig. 2j, inclusive, illustrate the successive steps in the formation of a pasted bag bottom by means of the present invention;

Fig. 3 is a side elevation of the novel tube end opening means employed in the present invention;

Fig. 4 is a detailed transverse view of a pair of suction cups employed on the tube opening device shown in Fig. 3, such cups being in a closed position;

Fig. 5 is a transverse view of such suction cups shown in Fig. 4 but in a spread condition, said figure also illustrating the immediately adjacent means for mounting the suction cups;

Fig. 6 is a view partly in section and with parts broken away of the tube end opening apparatus taken substantially on line 6-6 also of Fig. 3;

Fig. 7 is a sectional view taken substantially on line 7-7 of Fig. 3.

Fig. 8 is a side elevation of one half portion of the conveyor means for moving the tube end spreader units, that is, it illustrates one of the pairs of endless chain devices which are employed in such conveyor means;

Fig. 9 illustrates the other half of such tube end spreader unit conveyor means and illustrates the position of a plurality of individual spreader units which are mounted thereupon;

Fig. 10 is a side elevation, partly in section and with parts broken away, showing on an enlarged scale one of the tube end spreader units illustrated in Fig. 9 and also showing in detail portions of the means for mounting such unit upon its conveyor means and the operative association of such spreader unit with control means therefor;

Fig. 11 is an end view of the tube end spreader unit shown in Fig. 10;

Fig. 12 is a fragmentary detailed view of a portion of a flexible spreader plate employed in the tube end spreader unit;

Fig. 13 is a plan view of a tube end spreader unit, such as that shown in Fig. 10 but with parts thereof in a different operative position and also showing the manner of associating such tube end spreader unit with conveyor means therefor;

Fig. 14 is a side elevation of the tube end spreader unit shown in Fig. 13 with the spreader tongues thereof retracted into the frame of the unit;

Fig. 15 is a perspective schematic view of the conveyor means for the spreader units; and

Fig. 16 is a view of an opened and spread bag tube and illustrative of the several parts thereof.

The form of the invention illustrated in the accompanying drawings, by way of example, comprises apparatus for operating upon the ends of a previously formed bag tube, or a succession of such tubes, preferably of the multi-wall stepped end variety, whereby automatically the bag tube end is opened and thereafter corner and end flaps are formed thereon and the tube end is prepared to be closed and sealed, with the exception of the bag valve. Of course, if desired, one or both ends of a bag tube can be formed into a bottom with or without a valve.

Referring to the drawings in greater detail, the novel elements described herein are designed for use with a continuously driven bag tube conveyor. The present invention employs in combination with the above-mentioned elements for acting upon the tube ends, a master bag tube conveying means having a plurality of equally spaced bag tube gripping devices thereon by which the bag tubes may be successively grasped and continuously advanced to the various operating stations at a uniform but adjustable speed. As shown in Fig. 2, a pair of such gripping devices is shown at 21, 22 which are designed for grasping the leading edge of a bag tube and urging it in the direction of the arrow 23 to such various operating stations. A common power source is employed for driving not only the bag tube conveyor means but also all of the various units which act upon the bag tube and in particular the improved elements to be set forth herebelow. Suitable means are provided, however, for altering the phase adjustments of the novel elements for opening the tube ends and spreading same, together with certain of the other units, whereby they can be adjusted as desired while the apparatus is in operation.

The bag tube grippers 21 and 22 (Fig. 2a) are mounted upon a pair of synchronously driven endless sprocket chains or belts and are adapted successively to grasp, together with numerous other similar pairs of grippers, bag tubes and to pull same through the machine. The bag tube grippers act in pairs, one gripper of each pair

being mounted upon each sprocket chain. Each pair of grippers is automatically closed simultaneously to grip a bag tube and the tubes are consecutively and automatically advanced to the grippers by a suitable feeder mechanism (not shown). After each bag tube has been pulled through the apparatus and a bag bottom is formed thereupon, the grippers are automatically and successively opened and the completed bags delivered therefrom seriatim.

Referring now to Figs. 1 and 1a, the novel apparatus is constituted by a main frame 24 upon which are mounted the various operating units and said bag conveyor means. In the form shown, the latter comprises a pair of endless sprocket chains 25 and 26 (Fig. 2a) which are respectively stretched between suitable pairs of sprocket wheels (not shown). The path of the conveyors 25 and 26 is shown in side elevation in Fig. 1 schematically by the broken line 27 and indicates in general the path of the bag tubes as they are drawn through the various operating units of the apparatus.

A bag tube as at 28 (Fig. 2) having been grasped by the grippers 21 and 22 preferably has the ends thereof slit as at 29 by a suitable slitting device (not shown). Thereafter the bag tube is scored near the extremities thereof as at 30 by means of a suitable scoring unit indicated generally at 31 (Fig. 1). Then the tube ends as at 28a and 28b are bent or angularly shifted through preferably about 90° to a position which is perpendicular to the main body of the bag tube as illustrated in Fig. 2c whereupon the bag tube is prepared to the action of the novel tube end opener and thereafter the novel tube end spreader. The latter is effective to form the side and corner flaps thereupon as above explained. However, the invention is not limited to operation upon a bag tube which has had the ends thereof bent to a vertical position as shown in Fig. 2c, it being possible for the novel elements to act satisfactorily upon tube ends which are in the same plane with the main tube body.

Tube end opener.—Novel means, as above mentioned, are provided for opening the bag tube ends, which means in general are constituted by a suction device which is designed to travel linearly with a conveyed bag tube thereby to gain a positive grasp on the opposite sides of the end of the bag tubes, to open it and thereafter release it after the tube end spreader, to be described more fully hereinafter, has entered the opened tube end to perform the operation of forming the corner and side flaps.

Referring now to Figs. 1, 2c, 2d, 2e, and Figs. 3-7, inclusive, such novel tube end opening apparatus is illustrated generally at 32 (Fig. 1). Such means are constituted by a plurality of pairs of suction cups which are constructed and arranged for grasping, as above mentioned, the successive tube ends and for advancing linearly therewith along the path thereof for a selected distance, and simultaneously for opening same. As shown in Fig. 7, a typical pair of such suction cups is shown at 33, 34. These cups are respectively mounted upon endless chains 35 and 36 which travel at the same speed as the bag tube and accompany it for such selected distance as is well shown in Fig. 7. The endless sprocket chains 35 and 36 are mounted upon suitable pairs of sprocket wheels 37, 38 and 39, 40, respectively. Such sprocket wheels are also referred to as end pinions. Power is communi-

cated to the endless chains 35 and 36 by means of substantially centrally located sprocket wheels or pinions 41 and 42, respectively, which are mounted upon power shafts 43 and 44, respectively. It will be noted that the endless chains are situated in a common plane which, as is well shown in Fig. 3, is slightly inclined downwardly in the direction of the motion of the bag tubes, that is, the righthand extremity of the belts, as viewed in Fig. 3, is somewhat lower than the lefthand extremity thereof. The reason for so lowering such righthand extremity is to maintain the suction face of each pair of suction cups approximately in the same location relative to each bag tube end. This is to insure that each pair of cooperating suction cups grasps substantially the same area of each tube end as it progresses along the path of movement of the bag tube because as the pairs of suction cups are opened, they shift upwardly, as is evident from examining Figs. 4 and 5. Consequently it is necessary to compensate for this upward shifting of the suction cups by so tilting downwardly the endless chains in the manner shown in Fig. 3.

Referring to Fig. 3, it is seen that the sprocket wheels 39 and 40 are mounted upon a supporting frame 45 having upstream and downstream extending arms as at 45a and 45b, respectively.

In order to assist each pair of suction cups, as at 33, 34 (Fig. 7), in gaining a positive initial suction or grasp upon an oncoming tube end, so-called back-up idler sprocket wheels are provided for the chains 35 and 36 as at 46 and 47, respectively, said wheels being located immediately adjacent and in alignment with the areas of the bag tubes which are initially grasped by the tubes 33, 34.

The manner of mounting each pair of suction cups 33, 34 upon their respective endless sprocket chains is well shown in Figs. 4 and 5 and will now be described. In these figures said cups 33 and 34 are respectively pivotally secured to downwardly extending supporting arms 48 and 49 by pivotal mountings as at 50 and 51, respectively. Said arms 48 and 49 in turn are rigidly secured to their respective chains 35 and 36 by means of suitable bifurcated brackets as at 52 and 53, respectively.

As is well shown in Fig. 5, suction is communicated to each suction cup by means of a central passage existing in each of the supporting arms 48 and 49. For example, a passage 49a is formed in the arm 49 which is in communication via the pivot means 51 with a central passage 34a formed in the suction cup 34 and the supporting tubular structure therefor as at 34b. It is, of course, understood that analogous structure is employed in connection with suction cup 33 and its supporting arm 48, designated at 48a, 33a and 33b. The supporting arms 48 and 49 have secured thereto and preferably integral therewith upwardly extending hose connector portions 48b, 49b, respectively. To the latter are secured flexible hoses 54 and 55, respectively, which are connected to their respective revolving sleeve hose connectors, one of which is shown as at 56 (Fig. 3) as for the flexible hoses 55 and 55a. Such connector 56 is also referred to as a suction sleeve and is provided with suitable orifices for the connection thereto of the hoses such as 55 and 55a (Fig. 3).

Of course, it is necessary to rotate the suction sleeve 56 (and its counterpart associated with chain 35) in order that the hoses, such as 75 54, 55 (Fig. 5) may follow their respective suction

cups around the path of movement thereof, which, of course, constitutes the movement of their respective conveyor chains 35 and 36.

Each pair of suction cups as at 33, 34 (Figs. 4 and 5) thus is subjected to the following movements after it grasps a tube end (Fig. 4): (a) linear or translational movement from left to right, as viewed in Fig. 7, in the direction of motion of the bag tube; (b) angular movement about the respective pivots 50 and 51 wherein each suction cup is tilted upwardly from the position shown in Fig. 4 to that shown in Fig. 5; (c) movement away from one another, that is, movement transverse to the direction of movement of the bag tube whereby the cups are spread apart and are moved from the position close to one another, as shown in Fig. 4, to the spread apart and tilted position shown in Fig. 5; (d) a lowering movement, that is, the suction cups are lowered relative to the plane of the main body of the bag from the elevated position shown in Fig. 4 to the depressed position shown in Fig. 5, such movement being attributed to the tilting of the endless chains 35 and 36 in a downward direction, as shown in Fig. 3; that is, with the downstream extremity of the chain lower than the upstream, such tilting being in the direction of motion of the bag tubes.

The tilting or angular movement of the suction cups 33, 34, about the pivots 50, 51 is controlled by a cam action through the intermediary of a cam follower roller for each cup which coacts with a guide or cam member. As shown in Figs. 3-5, inclusive, it will be seen that the suction cups 33, 34 have operatively associated therewith the rollers 59 and 60, respectively, which in turn ride upon the guides or cams 61, 62, respectively.

Referring to Fig. 3, the guide or cam 62 is well illustrated showing an inclination thereof relative to the plane of the endless chain 36, which inclination effects the angular movement of the suction cup 34 about the pivot 51, it being understood, of course, that the guide 61 is similarly disposed relative to the sprocket chain 35.

The guides 61 and 62 may extend underneath their respective chains 35 and 36 throughout the lengths of such chains, if desired, wherein the rollers 59 and 60 are at all times resting upon their respective guides. However, if desired, the cams or guides may be provided only for a portion of the length of their respective chains, namely, beneath the so-called "inner runs" thereof. For example, the guide 61 may extend to the point 61a (Fig. 7) in a counterclockwise direction beneath the chain 35 and thence to the right in a downstream direction to the point 61b, and similarly the guide 62 may extend from an analogous point 62a in a clockwise direction around a portion of the pinion 39 and thence beneath the chain 36 to a point 62b. However, as shown in Fig. 6, the guides 61 and 62 are co-extensive with their respective chains, that is, they extent therebeneath throughout the length thereof.

In the form of the invention shown, with particular reference to Figs. 3-7, inclusive, each endless chain has secured thereto only two suction cups and each of these cups is synchronized in motion with a corresponding cup on the opposite endless chain or conveyor so that a pair of suction cups is brought into the relationship shown as at 33, 34 (Fig. 4), the axes of which are in alignment, such suction cups being referred to as "opposed suction cups." The lengths of the chains 35, 36 are so selected that the distance between the axes

of the sprocket wheels 37, 38 and 39, 40 requires only that two suction cups be affixed to each such chain. However, if the latter chains were longer, additional suction cups could be employed.

As shown in Fig. 7, when one pair of suction cups has opened and released a bag tube end, the second pair of suction cups will be in position for shortly grasping the next oncoming bag tube end.

Referring now to Figs. 1 and 6, the mechanism for communicating torque to the shafts 43, 44 and to said suction sleeves, together with certain of their related parts, will now be described. A common driving means, such as an electric motor (not shown) provides a torque for driving the entire apparatus and such motor may be operatively connected to a main power shaft 63 (Fig. 1) which extends substantially the full length of the apparatus and is rotatably mounted upon one side of the frame 24 by means of suitable brackets, as at 64. Extending across the path of the bag tubes transversely thereto is a so-called transverse power shaft 65 which is best shown in Fig. 6. This shaft is drivably connected to the endless chains 35, 36 and to the suction sleeves, as will appear more fully herebelow. Torque from the main power shaft 63 is communicated to the transversely extending shaft 65 through the intermediary of a gear train as follows: a gear 66 upon the shaft 63 meshes with a gear 67 upon an intermediate shaft 68, the latter through suitable miter gears located within a housing 69 communicates torque to a vertical shaft 70 which is operatively connected to said shaft 65 also through miter gears located within a housing 71.

In order to provide manually operable means for adjusting the phase relationship of the suction cups with the bag tube conveyor chains 25, 26 and hence with the bag tubes which are conveyed thereby, a manually adjustable differential 72 is interposed in the shaft 68, said differential having an adjustment knob as at 73, adjustment of which will effect desired phase adjustments of said suction cups with the oncoming bag tubes. It is understood, of course, that the suction cups upon both of the chains move in fixed phase relationship to one another by virtue of the geared interconnection between the driving means for the conveyor chains 35, 36 as will now be described.

Referring to Fig. 6, torque is communicated to shaft 44 which drives the conveyor chain 36 and to the shaft 43 which drives the chain 35 by means of miter gears 74 and 75 mounted respectively upon the shaft 65 and a shaft 76, the latter being mounted for rotation in suitable bearings upon a frame portion 77 of the tube end opener device. Rigidly secured to the shaft 76 is a gear 78 which communicates torque to an annular gear 79 which embraces and is rigidly secured to said suction sleeve 56. The latter is rotatably mounted upon a stationary tubular support 80 which in turn is secured rigidly to said frame portion 77, the shaft 44 being rotatably mounted within a passage 80a formed in the tubular support 80. The suction sleeve 56 is held against downward axial movement by means of an annular or ring retainer 81 which threadedly engages the support member 80 beneath the sleeve 56.

Rigidly secured to the upper extremity of the shaft 44 is a gear 82 which meshes with a gear 83 which in turn is rigidly secured beneath the miter gear 75 and which rotates therewith. Torque is communicated to the shaft 43 by means of gears 84 and 85 which are respectively

analogous to gears 83 and 82, the gear 85 being keyed to the shaft 43.

A rotatable suction sleeve 86 (analogous to sleeve 56) is provided for aiding in communicating a vacuum to the suction cups upon the chain 35 and torque is communicated to suction sleeve 86 by means of an annular gear 87 which embraces same and which meshes with an idler gear 87a which in turn engages the gear 78.

The suction sleeves 56 and 86 are driven in the same direction as the shafts 44 and 43, respectively, whereby the hoses which interconnect said sleeves with their respective suction cups are shifted around with the cups and do not become twisted or wound about the tubular support members as at 80. The shaft 43 is rotatably supported in a tubular support member 88 which is analogous to member 80 and is provided with a central passage 88a.

The hoses 55 and 55a interconnect the rotatable suction sleeve 56 with the suction cups 34, 34a (Fig. 6), and the hoses 54, 54a interconnect sleeve 86 with suction cups 33 and 33a.

Suction or vacuum is communicated to the hoses 54, 54a and 55, 55a as follows: The above suction sleeves 56 and 86 rotate about their respective tubular support members 80 and 88. The latter are provided with a plurality of passages in the cylindrical surface thereof, which passages periodically come into register with passages as at 56a and 56b of the hoses 55 and 55a.

Analogous structure is, of course, provided for the suction cups 33, 33a with respect to the suction sleeve 86 and the tubular support member 88. As is best also shown in Fig. 6, a suction passage 80b is provided in the tubular support 80 which communicates with the above-mentioned orifices which are movable into register with said passages 56a and 56b. Such an orifice is shown as at 80c.

Analogous suction passages and orifices are provided at 88b and 88c for the suction sleeve 86 (Fig. 6).

Tube end spreader means.—The tube end spreading means generally are divided into (a) a group of tube end spreader units, one of which units is shown as 89 (Fig. 9) and (b) conveyor means for said tube end spreader units, such means being indicated generally at 90 in Figs. 1, 3, 9 and 15. The tube end spreader units are also referred to as bag bottom flap forming elements and as will appear below are constructed and arranged for folding the open bag tube ends in such a manner positively to form the corner and side flaps for the bag bottom.

Regarding the conveyor means for the tube end spreader units, reference is made to Figs. 8, 9 and 15, particularly the latter, wherein there are shown means for moving such tube end spreader units upon an endless conveyor in such a manner that a vertical axis 91 of a spreader unit as at 89 is maintained continuously in a vertical relationship to the main body portions of the bag 28 (Fig. 2c) as they are moved through the apparatus. Thus said axis 91 is maintained continuously in a vertical relationship to the score line 30. If the latter is omitted and the tube ends are not bent in the manner shown in Fig. 2c, said axis 91 is maintained in a constant attitude relative to the bag.

Such conveyor means are constituted by a pair of endless conveyors, as at 92 and 93, said conveyors being of the belt variety and preferably comprising sprocket chains which pass re-

spectively over pairs of pinions or sprocket wheels 94, 95 and 96, 97 as is best shown in Fig. 15. The corresponding wheels of each pair thereof are parallel and positioned substantially side by side in an overlapping but spaced relationship with the axes thereof parallel but spaced apart by a preselected distance preferably in a common horizontal plane. For example, corresponding wheels 94 and 96 are parallel with the axes 94a and 96a thereof, respectively, being parallel but spaced apart a preselected distance indicated at 98 in a common plane which in the present instance happens to be horizontal.

The endless conveyors 92 and 93 are driven at a common speed by suitable means to be set forth hereinafter.

The corresponding sprocket wheels 95 and 97 are situated relative to one another in a manner analogous to that of wheels 94 and 96. The axial distances between the pairs of wheels 94, 95 and 96, 97 are the same.

For purposes of clarity, only a portion of a tube end spreader frame, as at 89a (Fig. 15) is shown in order to illustrate the manner of mounting the tube end spreader unit upon the two conveyors 92, 93. The frame portion 89a is rectangular and is provided with rollers 99, 100 and 101, 102 located respectively one at each corner thereof. Rollers 99, 100 rest upon a track 103 (Fig. 15) and rollers 101, 102 upon a track 104. It will be explained in connection with Figs. 10 and 11 that the said rollers in fact are moved in grooves over a substantial portion of their orbits whereby each roller is engaged by a rail at diametrically opposite sides thereof. However, for purposes of clarity single rails as at 103, 104 will be described in connection with Fig. 15.

The tube end spreader frame portion 89a is secured to the chains 92 and 93 at diagonally opposed locations, namely, at 105 and 106, said locations being separated by a distance, measured along said conveyors, equal to said preselected distance 98, such distance being indicated as at 107.

It will be seen that when the conveyor belts or chains 92, 93 are moved in a counterclockwise direction, as indicated by the arrow 108, said frame member 89a will be shifted such that the juncture points 105 and 106 will be angularly shifted about the wheels 94 and 96 simultaneously and at the same angular speed. Due to the spacing of the wheel axes by the distance 98, the axis 91 will remain constant in attitude, for example, vertical, as the spreader unit is lowered. In order to steady said frame 89a as it so descends, a guide member 109 is provided for engaging the roller 101.

Thus the rollers 100 and 101 do not follow and move alongside of their respective chains 92 and 93 during the downward angular movement.

When spreader unit 89 nears the righthand extremity of its orbit in the neighborhood of the wheels 95, 97, the upward angular movement thereof onto the upper runs of the chains is assisted and steadied by a guide 110 comprising a rail member for engaging the roller 100 in a manner analogous to the coaction of the roller 101 and the guide 109.

The movement of the tube end spreader units mounted upon the conveyors 92, 93 is, of course, synchronized with the movement of the conveyor chains 25, 26 whereby a spreader unit is lowered into each opened tube end, as shown in

Fig. 2e. The phase relation of the spreader units and the conveyor chains 25, 26 can be adjusted by a hand adjustable differential in the torque power line for the pinions 94, 96 and 95, 97. Such torque transmission line includes shafts 63a (Figs. 1 and 2) and 63b which are powered by shaft 63. Interposed in the former is the above-mentioned differential as at 63c having a knob at 63d.

It has been found desirable to select the length of conveyors 92, 93 to accommodate seven tube end spreader units 89, it being possible to produce accurately a heretofore unattained number of folded bag bottoms per minute with this number of spreader units.

The distance between the axes of, for example, wheels 95 and 97 has been selected in order to permit each tube end spreader to perform its function with sufficient time so that there will be no undue haste in the operation thereof. That is, the distance between such axes should be sufficient to allow time enough for each tube end spreader to act without any injurious shocks to the bag tubes and to the machine when the rate of motion of the bag tube conveyor is high.

For purposes of clarity as above mentioned the rail means for guiding the tube end spreader units 89 are not fully illustrated in Fig. 15. For such full illustration reference is made to Figs. 8-11, inclusive, with particular reference to Figs. 9 and 11. In Fig 11 it is seen that the rollers 99-102, inclusive (99 and 101 of which are shown), move within the tracks 103 and 104, that is, the rollers 99, 100 move in the tracks 103 and 101, 102 in the track 104. These tracks are of the so-called grooved variety wherein the distance between the tracks, for example, the distance between portion 103a and 103b (Fig. 11) (or between 104a and 104b) is slightly in excess of the outer diameter of the roller 99 whereby a close control is maintained over the direction of said roller and the tube end spreader unit is prevented from wobbling or angularly shifting while moving along the lower runs of the conveyors 92, 93. The same is true of the rail structure along the upper runs of said conveyors or chains.

The chains 92 and 93 preferably move between flanges 103c, 103d and 104c, 104d as is best shown in Fig. 11. These flanges are equal in length to that of the guide rails 103 and 104.

The upper and lower portions of the tracks 103 and 104 are approximately of equal length, such length being about equal to the distance between the centers of their respective wheels 94, 95 and 96, 97.

The guide members 109 and 110 for steadyng the spreader units during their lowering and raising are provided with suitable entrances and exits to facilitate the movement of a roller as at 101 into guide 109, and roller 101 into the guide 110.

A conveyor frame generally indicated as at 111 (Fig. 8) is provided upon which the shafts or journals are mounted for the conveyor wheels 94, 95 and 96, 97. It is desirable to provide means for controlling the tension upon the conveyor belts or chains 92, 93 by adjusting the axial distances between the wheels 94, 96 and 95, 97. The means for accomplishing this are shown in Fig. 8 and constitute a movable mounting for the wheels 94, 96, such mounting being adjustable and generally indicated at 112. The latter comprises a pedestal 113 for supporting a wheel bracket 114 which is somewhat in the shape of

an inverted L having a face as at 114a which rests upon a supporting face 113a of the pedestal 113. By means of threaded adjustment bolts 115, 116 it is possible to shift the bracket 114 and hence wheels 94, 96 to the left or to the right, as viewed in Fig. 8.

Tube end spreader unit.—As has been mentioned above, there are preferably several tube end spreader units employed in the tube end spreader means. They are mounted at equally spaced intervals upon the conveyors 92, 93 in the manner described above concerning Figs. 9 and 15.

Referring to Figs. 10-14, a tube end spreader unit (or side and corner flap folding or forming unit) is constituted by a pair of spacer members 117 and 118 (Fig. 13). Spacer member 117, as viewed in Fig. 14, consists of a main vertical support 117a near the upper portion thereof. Below the arms 119 and 120 are outwardly extending arms 121 and 122 which also extend coaxially and perpendicularly to the vertical portion 117a in opposite directions and differ from the adjustment arms 119 and 120 in that they are of rectangular instead of circular cross-section.

It will be understood that the other spacer member 118 is provided with arms as at 123 and 124 (Fig. 13) which are analogous to the adjustment arms 119 and 120 and with arms which are analogous to 121 and 122, one of such arms being indicated at 125 (Fig. 11).

The spacer members 117 and 118 provide means for adjusting in spaced relationship spreader plate guide members 126 and 127. The latter are generally U-shaped, for a purpose to appear later, as is well shown in connection with member 126 (Fig. 11). Referring to Fig. 13, it will be seen that the plate guide member 126 is provided with bores for receiving the arms 119 and 123, such bores being indicated as at 126a and 126b. Furthermore, the plate guide member 126 is provided with grooved arms as at 128 and 129 for engaging the spacer arms 121 and 125 as is well shown in Fig. 11.

By means of the above-described spacer mechanism for the tube end spreader unit, it will be seen that the plate guide members 126 and 127 may be adjusted in their spaced relationship from the position shown in Fig. 10 wherein they are closely adjacent one another, to the widely separated position shown in Fig. 14. The reason for providing for such adjustment is to increase the so-called "universality" of the apparatus with respect to the size of bag widths which the machine can accommodate, that is, to provide for a wide variety of sizes of bag widths upon which there can successfully be formed the side and corner flaps above mentioned in connection with Fig. 2.

Referring to Fig. 16, the term "bag width" refers to the dimension 130 measured between the outer peaks of the corner flaps indicated as at 131 and 132. The term "bottom width" refers to the dimension 133 which is measured between the bottom fold lines indicated at 134 and 135.

The plate guide members 126 and 127 are provided with slotted guide portions indicated at 136 and 137, respectively, in which there are movable vertically spreader plates 138 and 139 which are retractile relative to such guide members as will now appear.

The outer extremities of spreader plates 138 and 139 are urged by means of suitable guides to move in opposite directions, that is, the outer extremities thereof 138a and 139a are guided to move in opposite directions. Such guiding means for the spreader plate 138 are well shown in Fig. 14 consisting of a roller 140 and a curved guide 141. An analogous roller and curved guide for the spreader plate 139 are shown at 142 and 143, respectively.

By simultaneously urging downwardly the upper extremities 138b, 139b of the spreader plates 138 and 139 it will be seen that said plates will be extended outwardly to the position shown in Fig. 13.

The mechanism for communicating upward downward movement to said plate extremities 138b, 139b is best shown in Figs. 9-14, inclusive, and is constituted by an adjustable cam indicated generally at 144 (Fig. 9) which is in the shape of a flat V and which cooperates with a follower 145 (Fig. 10) which in turn is connected to a wrist pin 146, the latter being secured by resilient means to the upper extremities 138b and 139b of said spreader plates. The cam follower or roller 145 is mounted upon an arm 147 which in turn is secured rigidly to said wrist pin 146. In order to guide the vertical movement of ascent and descent of the wrist pin 146 and its connected cam follower 145, a suitable guide carriage is provided as at 148 (Figs. 10 and 13) which preferably is rectangular in shape and has mounted at each of the corners thereof rollers 149. Such rollers consist of groups of two on each side of the carriage 148 and each such group moves in a vertical guideway 150. The carriage 148, of course, is also rigidly secured to the wrist pin 146 and the vertical oscillating of such pin is thus made steady without wobble. The axis of the pin 146 is thus maintained in a horizontal plane, as viewed in Fig. 14.

In addition to the four rollers 149 which are secured to the corners of the rectangular carriage 148, the guide means for the wrist pin 146 includes a pair of rollers 149a, one secured to each vertical side of the carriage, as is best illustrated in Fig. 13. These rollers are movable upon plates 150a and the axes thereof are perpendicular to those of rollers 149.

The extent of the vertical movement of the guide carriage 148 and, of course, the follower 145 is controlled by the angle at which the arms of the V-shaped cam 144 are disposed relative to their vertical axis. As is shown in Fig. 9, the cam 144 is constituted by a left arm 144a, a right arm 144b and a center section 144c. The latter section may be raised and lowered by any suitable mechanism, one form of which will be described hereinafter. The arms 144a and 144b are so mounted at the extremities thereof that the center section 144c may be raised or lowered with such arms spreading outwardly and pivoting slightly but maintaining a common angle to said vertical axis.

Said raising and lowering of the mechanism, in the form shown, is constituted by a manually controlled knob or wheel 151 which communicates said adjusting vertical movement to the center section 144c by means of a worm and wheel device indicated generally at 152 (Fig. 9). This latter mechanism includes a vertical threaded shaft 153 which is embraced by an axially stationary sleeve 154 to which is secured a worm wheel 155 which is under the influence of a worm 156, the latter having a shaft which

is shown as at 157 (Fig. 8) and constitutes the shaft of the handwheel 151.

It is desirable to provide a cushioning means for resiliently transmitting the downward thrust of the wrist pin 146 to the flexible plates 138 and 139. Such cushioning means for plate 138 are shown generally at 158 (Fig. 11) and are constituted by, for example, a cushioning spring 159 which, as viewed in Fig. 11, thrusts upwardly against a wrist pin journal member 160, the latter being slidably mounted within a slotted guide 161. Normally the spring 159 urges the journal member 160 against an upper limit-stop of the guide 161. There, of course, is a similar cushioning device for the opposite extremity of the wrist pin 146, i.e., for plate 139.

By virtue of this cushioning device, the possibility of tearing the bag tube ends is substantially reduced and a yielding or resilient thrust is provided which urges the spreader plates 138 and 139 in opposite directions outwardly as viewed in Fig. 13.

The outer extremities 138a, 139a of the plates 138 and 139 have secured thereto respectively corner flap shapers 138c, 139c (Fig. 13) respectively. These shapers are also referred to as corner flap mandrels. Such shapers are preferably constituted by two portions which are separated by 90°, that is, a portion as at 138c' is situated 45° relative to a central axis of the spreader plate 138 and the other portion 138c'' is similarly situated on the opposite side of such axis.

Further in connection with the extent of separation of the guide members 126 and 127 (Fig. 14), it is, of course, understood that these members can be secured in any desired separated position within the limits of the arms 119, 120 and such adjustments must be made while the apparatus is stationary.

Thus the extent of the separation of the points of the corner flap shaper members 138c and 139c can be adjusted by (a) moving the guide members 126 and 127 to desired positions upon the arms 119, 120 and 123, 124; and (b) by adjusting the handwheel 151 which controls the angularity of the arms 144a, 144b of the cam 144. The latter adjustment is normally for fine adjustments and can be made while the machine is running.

Such fine adjustments, for example, may be of one-eighth inch or one-quarter inch in the extent of separation of said spreader points. For any larger adjustments it has been found desirable practice to effect same while the apparatus is stationary by adjusting the separation of the guide members 126, 127.

The guide members 126, 127 are generally U-shaped as is best shown in Fig. 11 for member 126 because such conformation accommodates the vertical oscillatory movement of the wrist pin 146.

In operation, a succession of bag tubes are grasped by the grippers 21 and 22 and moved by means of the conveyors 25, 26 through the apparatus, the slits 29 and score lines 30 being formed as above mentioned (Figs. 2a and 2b). Thereafter the bag tube ends 28a and 28b are bent at right angles to the main body of the bag, as shown in Fig. 2c, and suction cups grasp each of the tube ends for opening same. For example, as shown in Fig. 2c, a pair 33, 34 grasps the tube end 28b and gradually opens same as it progresses along the path of the tube end, as explained in connection with Figs. 3, 4 and 5. A tube end spreader unit is thereafter lowered (Fig. 2e) into

each of the open tube ends, such lowering occurring with the axis 91 thereof perpendicular to the main body of the bag tube. Each tube end spreader unit accomplishes an initial flattening and spreading of the open tube end by virtue of such lowering and under the action of the spreader plate control mechanism, including the V-shaped cam 144, and its follower mechanism, the points of the spreader plates are gradually separated to a desired and finely adjustable extent, as best shown in Fig. 2f, whereupon the bag tube corner portions are positively and forcefully caused to fold over the corner flap shaping members 138c and 139c, forming the corner flaps 131 and 132 and forming positive diagonal fold lines 131a, 131b and 132a, 132b. Also side flaps 28a and 28b are positively spread out as a result of the positive folding of the corner flaps over their respective shaping members. The points of the spreader tongues or plates are thereafter retracted from the position shown in Figs. 2f and 13 to that shown in Fig. 14 also under the action of the cam 144 whereupon the bag tube is in the condition shown in Fig. 2g.

Thereafter said tube is acted upon by mechanism to complete the forming of the bag bottom as disclosed in the above-mentioned copending application Serial No. 48,820, filed September 11, 1948, by Edwin E. Burroughs (now Patent No. 2,570,047). That is, the tube ends are pressed as by pressing rollers indicated generally at 162 and thereafter the bottom fold or score lines are formed as at 163 (Fig. 2g) by a scoring device 164. Paste is then applied, as shown in Figs. 2h and 2i, by a suitable gluing device 165, a sleeve inserted by sleeving means 166 and thereafter the side flaps are folded over and pressed to complete the forming of the bag bottom as shown in Fig. 2j.

There is thus provided a novel apparatus for acting upon bag tube ends for forming bag bottoms wherein the tube ends are positively opened by suction means which are capable of moving with the bag tube ends for a sufficient time to allow the suction cups thereof to obtain a positive grasp thereupon whereby there is no failure in the pulling open of the tube ends because this structure is so constructed and arranged that the spreading of the suction cups does not occur until sufficient time is allowed to obtain such a positive grasp. The tube end spreader means are capable of accommodating with great accuracy a wide variety of bag widths and forming side and corner flaps in a positive and rapid manner without shock or damage to the tube means and in such a manner that the diagonal fold line of the corner flaps are formed with great precision whereby the percentage of defective bag bottoms formed is substantially eliminated. Furthermore, while the machine is in operation, fine adjustments in the separation of the spreader points can be made which permits of an increased output by reducing the time when the apparatus is shut down for adjustment.

While the invention has been described with respect to a certain preferred example which has given satisfactory results it will be understood by those skilled in the art, after understanding the invention, that various changes and modifications may be made without departing from the spirit and scope of the invention, and it is intended, therefore, in the appended claims to cover all such changes and modifications.

What is claimed is:

1. In apparatus for forming the ends of bag

5 tubes, the combination comprising: a conveyor for moving such tubes; a pair of suction cups; means for moving said cups linearly along the path of movement of such bag tubes; means for mounting said cups for pivotal movement relative to one another, means for pivotally moving said cups from a closed-opposed position with the mouths thereof adjacent one another to an open position with such mouths separated, said 10 cups, moving and mounting means being positioned and controlled for grasping the opposite sides of a closed end of a bag tube and opening same, said means for so linearly moving said cups being operable simultaneously with said means for so pivotally moving said cups; a flap folding device for acting upon an open tube end comprising a frame member, a pair of tongue guide members adjustably secured to said frame members, a pair of flexible tongues mounted for sliding movement in said guide members, the latter directing the outer extremities of each of said tongue members in opposite directions, means for slidably moving said tongues simultaneously relative to said guide members whereby such tongues can be extended or retracted, each of said tongues having a substantially V-shaped forming element secured to its outer extremity; and means for moving said flap folding device in timed relation to said conveyor and to a bag tube moved thereby, such moving means being constructed and arranged for inserting said folding device into the end of a bag tube which has been opened by said suction cup means and for actuating said tongues positively to form corner and side flaps upon the tube end.

2. A bag bottom flap forming element including a frame member, a pair of guide members mounted in parallel relationship upon said frame member, the latter being constructed and arranged for permitting adjustment of the spaced relationship of said guide members, a pair of flexible plate members comprising tongues each being mounted in one of said guide members and adapted for sliding movement therein, said tongues having inner and outer extremities, the outer extremities thereof being directed in opposite directions by said guide members, and means for operatively interconnecting such inner tongue extremities whereby said tongues can be synchronously retracted or extended.

3. In an automatic bag bottom forming apparatus of a class having a bag tube conveyor including spaced gripping means for consecutively gripping a plurality of bag tubes along the leading edge of each tube and moving same in succession relative to said apparatus along a common path, a pair of suction cups; means for creating a partial vacuum in such cups; means for moving said pair of cups linearly along such path; means for controlling the spaced relation of said cups comprising cam means for urging the mouths thereof together for gripping opposite faces of a bag tube end during the initial portion of such linear movement, said cam means being constructed and arranged gradually to spread said cups apart progressively with such linear movement until the tube end is opened; bag bottom flap forming means comprising a frame member having therein retractilely mounted a pair of flap spreader tongues the outer extremities of which are directed in opposite directions; means for moving said flap forming means into the end of a bag tube opened by said suction cups, said means also moving such means linearly along said path; and means for extending and retracting said tongues

in timed relation with the movement of said conveyor.

4. In an automatic bag bottom forming apparatus, a bag tube conveyor including spaced gripping means for consecutively gripping a plurality of bag tubes near opposite extremities along the leading edge of each tube and moving same in succession relative to said apparatus in preselected spaced relationship along a common path; tube end opening means including a pair of endless belts, each having a like plurality of suction cups mounted thereon in spaced relation, said belts being positioned side by side and in substantially the same plane, whereby a side-run of one belt is adjacent a side-run of the other belt, said belts and cups thereon being movable in synchronism whereby opposed pairs of cups are movable in phase with one another, each such pair including one cup on each belt, means for mounting each of said cups for pivotal movement relative to its belt, and cam means for controlling the angular relation of the cups of each opposed pair thereof whereby each such pair is moved from a closed position progressively to an open one while undergoing linear movement in the direction of said conveyor, a tube end therebetween thereby being progressively opened; bag bottom flap forming means including a plurality of spreader units, a pair of endless belts for moving and mounting said units, each of such belts being mounted upon a pair of wheels, corresponding wheels of each pair thereof being substantially parallel and positioned substantially side by side in overlapping relation and with the axes thereof parallel, said axes being spaced apart by a preselected distance in a common plane, said units being secured jointly to said belts at two locations, one for each belt, said locations being separated by a distance, measured along said belts, equal to said preselected distance whereby each of said units is movable along the path of said conveyor with an axis thereof always in a common attitude relative to the path of movement of the tubes moved by said conveyor, each of said spreader units including guide members and a pair of flexible tongue members retractile mounted in such guide members, the latter being so constructed and arranged that the outer end of said tongue members are directed in opposite directions, each outer end of a tongue member being provided with a V-shaped corner flap shaping member secured thereto; said spreader units being moved by said belts for acting successively upon the opened tube ends after being opened by said tube end opening means; and means for synchronously extending and retracting said pairs of tongue members in preselected relationship with the movement of said bag tube conveyor whereby a spreader unit is lowered into each oncoming opened tube end and moved therewith at the same speed thereof and corner and side flaps positively formed therein by said tongue members.

5. In an automatic bag bottom forming apparatus of the class having a bag tube conveyor including spaced gripping means for consecutively gripping a plurality of bag tubes near the opposite extremities and along the leading edge of each tube and moving same in succession relative to said apparatus, the combination comprising: tube end opening means including a pair of oppositely disposed suction cups for engaging opposite sides of the end of a bag tube and for pulling same open under the influence of suction and the movement of said cups, means for advancing said pair of suction cups along the path of said

conveyor for a substantial distance in order to allow said cups to grip a tube end, and means for simultaneously moving said pair of suction cups from a closed position wherein they grip a closed tube end, to an open position wherein said cups are spread apart and said tube end is opened by a preselected amount; and a flap forming device including a frame member, a pair of retractile flexible tongues mounted upon said frame member for extensible and retractile movement relative thereto, said frame member including guides for directing the outer extremities of said tongues for movement in opposite directions, means for simultaneously moving said flap forming device in the same direction and along with said bag tube conveyor, such last-named means inserting said device into a bag tube end which has been opened by said tube end opening means, means for extending and retracting said tongues while said flap forming device is so situated whereby side and corner flaps are positively formed in the tube end, and means for thereafter withdrawing said device from the open tube end.

6. In apparatus for automatically shaping the ends of bag tubes, such apparatus having a bag tube conveyor including spaced gripping means for consecutively gripping a plurality of bag tubes near opposite extremities along the leading edge of each tube and moving same in succession relative to said apparatus in preselected spaced relationship, the combination comprising: tube end opening means including a plurality of pairs of suction cups each adapted for grasping and pulling open the ends of a bag tube, the cups of each pair being mounted for movement relative to one another to accomplish such tube end opening, means for moving said pairs of cups linearly along the path of said conveyor, and means for simultaneously and progressively moving the cups of each pair from a closed position with the mouths thereof urged toward one another to a separated position; and a plurality of flap folding units each including a guide frame, a pair of flexible retractile tongues mounted in said guide frame, said tongues having inner and outer extremities, each of the outer extremities having secured thereto a flap shaping member, said guide frame guiding said outer extremities for motion in opposite directions, means for operatively associating the inner extremities of said tongues whereby a thrust thereupon simultaneously moves both the tongues; endless belt support means for said flap folding units for moving the latter into operative relation each with an open tube end as one of the latter moves into the orbit of said belt support means and a flap folding unit, means for operatively connecting said belt support means and said conveyor for movement in preselected phase relationship whereby said units are inserted successively into such open ends of successive bag tubes, and means for controlling the extension and retraction of said tongues when such units are so inserted.

7. In an automatic bag bottom forming apparatus the combination including a bag tube conveyor for moving continuously a plurality of bag tubes in succession along a common path and consecutively past a plurality of units for forming a bottom in each of such tubes; and a tube end opener including: a pair of endless belts situated adjacent to one another and in a common plane, the latter plane being inclined relative to said conveyor with the upstream extremities of said belts positioned at a greater distance from said conveyor than the downstream extremities

thereof, said belts having side runs which diverge from one another progressively in the direction of motion of said conveyor, a like plurality of suction cups mounted upon each of said belts in spaced relation thereon, said belts being movable in synchronism, each suction cup upon one of said belts having a corresponding and coacting suction cup upon the other belt, said corresponding suction cups thus comprising a pair thereof, one on each belt, said cups being movable in phase with one another, and means for angularly shifting said cups moving on adjacent side runs of said belts progressively from a closed-opposed to a separated relationship.

8. In an automatic apparatus for shaping an extremity of each bag tube of a succession thereof, a bag tube conveyor including means for continuously moving in succession a plurality of bag tubes along a common path; and a tube end opener including: a pair of endless belts having inner runs, means for mounting said belts with such inner runs thereof extending generally in the direction of motion of said conveyor and with such inner runs spaced from but movable alongside one another, a preselected portion of such inner runs progressively diverging from one another as measured when moving in the direction of said conveyor, said means for mounting said belts being disposed for inclining said inner belt runs relative to such conveyor, a plurality of pairs of suction cups mounted on said belts, the cups of each pair being mounted one on each belt and movable in phase relation with one another, means for operatively interconnecting said belts for synchronous movement, and means for angularly shifting the cups of each pair thereof moving on adjacent side runs of said belts progressively from a closed-opposed to a separated relationship.

9. In an automatic apparatus for shaping an extremity of each of a succession of bag tubes, a bag tube conveyor including means for continuously moving in succession a plurality of bag tubes along a common path past a unit for shaping an extremity of each of such tubes; and a tube end opener including: a pair of endless belts having inner and outer runs, means for mounting said belts with the inner runs thereof spaced from but alongside one another and movable in the same direction with said conveyor, a preselected portion of such inner runs being substantially parallel to one another, the remaining portion of such inner runs diverging from one another progressively along the path of movement of said conveyor, said inner runs also being inclined relative to such conveyor with the upstream extremities thereof located farther from said conveyor than the downstream extremities, a plurality of pairs of suction cups mounted on said belts, the cups of each pair being mounted one on each belt and movable linearly in phase with one another, and means for angularly shifting the cups of each pair moving on adjacent side runs of said belts progressively from a closed-opposed to a separated relationship.

10. In an automatic bag bottom forming apparatus the combination including, a bag tube conveyor for moving continuously a plurality of bag tubes in succession along a common path and consecutively past a plurality of units for forming bottoms in such tubes; a pair of endless belts positioned adjacent one another and alongside of said bag tube conveyor, each belt being mounted upon a pair of wheels, adjacent side runs of said belts extending along a common portion of the

path of said conveyor, such side runs being closest to one another at their upstream extremities and diverging from one another progressively toward the downstream extremities thereof; a like plurality of suction cups mounted upon each of said belts in spaced relation thereon, said belts and cups being movable in synchronism, opposed pairs of cups one on each belt being movable in phase with one another, said belts being located in substantially the same plane and tilted with the downstream extremities thereof lower than the upstream extremities, and means for angularly shifting each pair of said cups moving on said adjacent side run from a closed-opposed relationship to a separated relationship; and tube end spreader means for acting upon such opened tube ends including: a spreader unit, the latter comprising guide members and spreader tongues retractile mounted therein, conveyor means for moving such unit linearly in phase with said bag tube conveyor, and means for automatically and cyclically extending and retracting said spreader tongues during operation of said unit conveyor means.

15 25 30 35 40 45 50 55 60 65

11. In an automatic bag forming apparatus of the class having a bag tube conveyor including spaced gripping means for consecutively gripping a plurality of bag tubes near the opposite extremities and along the leading edge of each tube and moving same in succession relative to said apparatus, the combination comprising tube end opening means; and a flap forming device including a frame member, a pair of retractile flexible tongues mounted upon said frame member for extensile and retractile movement relative thereto, said frame member including guides having oppositely directed portions for directing the outer extremities of said tongue for movement in opposite directions, means for simultaneously moving said flap forming device in the same direction and along with said bag tube conveyor, said last named means including a pair of endless belt conveyors mounted in side-by-side relationship, each of such endless belts being mounted upon a pair of wheels, the corresponding wheels of each pair thereof being parallel and positioned side-by-side in an overlapping but spaced relationship with the axes thereof parallel but spaced apart by a preselected distance in a common plane, said frame member of such flap forming device being secured to said endless belts at two locations, one on each belt, said locations being separated by a distance measured along said conveyors equal to said preselected distance separating the axis of corresponding pairs of wheels thereof, said flap forming device conveyor belts being positioned for inserting said device in response to movement thereof into a bag tube end which has been opened by said tube end opening means, means for extending and retracting said flexible tongues in preselected phase relationship with the movement of said bag tube conveyor, and means for thereafter withdrawing said flap forming device away from said bag tube conveyor.
